CLAIM

The ornamental design for a stand for a hairdryer, as shown and described.

DESCRIPTION

FIG. 1 is a front elevational view of a stand for a hairdryer, showing my new design;
FIG. 2 is a perspective view thereof from below;
FIG. 3 is a side elevational view thereof;
FIG. 4 is a front elevational view thereof, the side opposite that shown in FIG. 4 being flat and plain; and
FIG. 5 is a plan view thereof.

The broken line showing of a cord and hair dryer in FIG. 1 is for illustrative purposes only and forms no part of the claimed design.

FIG. 1.
